UNITED STATES PATENT OFFICE.

JOHN W. HAWKINS, OF PORTLAND, OREGON.

JOINT-FASTENING.

1,030,088.

Specification of Letters Patent. Patented June 18, 1912.

Application filed May 31, 1911. Serial No. 630,534.

To all whom it may concern:

Be it known that I, JOHN W. HAWKINS, a citizen of the United States, residing at Portland, in the county of Multnomah and State of Oregon, have invented a certain new and useful Improvement in Joint-Fastenings, of which the following is a full, clear, and exact description, reference being had to the accompanying drawings.

10 This invention relates to joints for securing together the abutting ends of railroad rails, and has for its object the provision of a device of this type wherein the necessity for forming apertures in the rail ends is avoided, and in which the tightness of the joint shall increase with the weight and strain placed thereupon; the provision of a rail joint wherein a close equilibrium of strains shall be maintained

20 among the different members and in which the smallest amount of deterioration with use shall be experienced; the provision of a joint in which the rails shall be entirely free to expand and contract with changes

25 in temperature, in which the passage of a wheel from one rail to the other shall take place with the least possible noise and shock, and in which the rail must be elevated bodily in order to permit the dis-

30 mounting of the joint members.

Still other objects are the elimination of threaded means as a direct reliance for the securing together of the rail ends and the production of a joint having substantially the same bending moment or stiffness as that possessed by the rails at the sides of the joints, while further objects and advantages will be apparent in the course of the following description and claims.

40 One embodiment of my invention is illustrated in the drawings accompanying and forming a part hereof, wherein:

Figure 1 is a perspective view of a rail joint made in accordance with my invention and illustrating the method of securing the same to the ties, one of the rails being broken off adjacent the end of the joint; Fig. 2 is an end view of said joint showing the broken end of said rail; Fig. 3 is a top plan view of a portion of one of the wedge plates; Fig. 4 a top plan view of a portion of one of the master plates; Fig. 5 a top plan view of a portion of the rail showing the elongated notch in the base flange thereof; Fig. 6 a top plan view of a portion of

the bed plate; and Fig. 7 a perspective view of one of the bolts.

In order to be practical it is imperative that a rail joint be of a nature to be employed with rails of standard form and size so as to be applicable to existing conditions, since any joint which depended upon a total change in the rail design would inevitably fail of adoption. I have, therefore, illustrated my rail joint in connection with a rail of standard form and specifications, which rail consists of a flat head 3 connected by a vertical web 4 with a comparatively wide, flat base 5, the under side of the head and the upper surface of the base flange being flared away from each other at each side of the web, as indicated at 6 and 7, respectively.

At 1-1 I have indicated a pair of adjacent ties and at 2-2 the ends of two abutting lengths of rail of the kind described.

These rail ends are supported upon a bed plate 8 having adjacent each of its sides an upwardly extending rib 9 and having outside each of said ribs the laterally projecting flange 10 adapted to be engaged by the usual spikes for maintaining the plate in place upon the ties. The inner walls of the ribs 9-9 are inclined outwardly, as shown at 12, and the total distance between said ribs is preferably made somewhat greater than the width of the base 5 of the rail, as illustrated in Figs. 1 and 2. This construction provides a bed plate or chair having a rail receiving channel on its upper face. Mounted upon each side of the rail within the limits of the base plate is a master plate 13, the same comprising a substantially vertical web 14 adapted to substantially parallel the web 4 of the rail and having at its lower edge an outwardly and downwardly flared flange 15 adapted to rest evenly upon the surface 7 and having at its top a similar flange 16 shaped to engage the surface 6 of the rail head. The flange 15 extends laterally farther than the rail base 5 and is formed with a beveled surface 17 inclined oppositely to the surface 12 of the rib 9 from which it is separated by a narrow space. The outer face of the web 14 is formed with a horizontal recess 18 having its upper wall 19 inclined upwardly at an angle intermediate between the angles of the surfaces 6 and 12. Outside of this master plate is placed the wedge plate 20

which is formed with a horizontal web 21 having at its outer edge a downturned flange 22 and at its inner edge the upturned flange 23. The outer and inner faces of the flange 22 are beveled to correspond with the surfaces 12 and 17, respectively, and the upper edge of the flange 23 is beveled complementarily to the surface 19. The lower portion of the flange 23 is spaced away from the bottom of the recess 18, and the lower portion of the web 14 of the master plate is likewise spaced away from the web of the rail. Inasmuch as the two sides of the joints are absolutely identical it is thought that the detailed description of one will suffice for both.

In order to permit the application of the bolts thereto, the wedge plates 20 are formed with perforations 30 in their horizontal webs, the master plates 14 are formed with laterally extended notches 31 in their flanges 15, the sides of the rail base are formed with longitudinally extending notches 32, and the base of the bed plate is formed with elongated slots 33. A bolt of the form shown in Fig. 7 is preferably employed, having a flattened elongated head 34 adapted to be passed through the slot 33 from above and turned through an angle of ninety degrees to prevent disconnection therefrom, a squared portion 35 immediately above the head and adapted to be non-rotatably received in the slot 33, and a cylindrical shank 36 provided with threads 37 adapted to receive a nut 38. The notch 32 in the rail base is made elongated in order to accommodate the expansion and contraction of the rail, and the notches 31 in the master plates are extended laterally in order to permit the lateral movement of these plates to be described hereafter.

In order to assemble this joint the bed plates 8 are first placed upon the ties, the rail ends placed therein and the bolts inserted in the slots 33. The master plates 13 can now be applied thereto without hindrance, but in order to insert the wedge plates 20 it will be necessary to raise both rail ends and master plates inasmuch as the surfaces 12 and 19 are convergent. The total width of the wedge plate 20 is so chosen that the surfaces of the flanges will contact as closely as possible with all three surfaces at the same time. The ends of the rails are here shown as cut at an angle since this is the preferred method of abutting the two, but it is obvious that such a formation is not necessary to the practice of my invention.

Even though the bolts be omitted it will be seen that a completely operative joint is formed inasmuch as the joint can be dismounted only by raising the rail ends, and the weight of a wheel upon the rails will tend to force the parts together with added

firmness. This is particularly true in case the width of the wedge plates 20 be so adjusted as to prevent the complete seating of the rail, since in this case the downward pressure upon the flanges 16 of the master plates will be supported by the flanges 23 of the wedge plates, and it is impossible for this pressure to occasion an outward crowding of the wedge plates because of the convergence of the surfaces 12 and 19. Neither is the inward crowding of these flanges possible because of the fact that the upper edges thereof are seated against the bottoms of the recesses 18. The only remaining possible motions are downward and outward movements of the flanges 22 which are prevented by the surfaces 12 and 17. It is therefore obvious that the tendency of an increased weight upon the rail will be to lock all the parts more firmly in their assembled position. The bolts, however, have a two-fold object, first in that they prevent the overturning of the rail, which might otherwise be possible, and second, in that they can be tightened up so as to partially raise or tend to raise the rail away from the bed plate, thus rendering unnecessary the exact adjustment of the width of the wedge plates. The effect of the bolts in preventing overturning will be obvious, but the effect of the same in raising the rail is not so clear. It will be noted that as the nuts are tightened the most obvious effect will be to wedge the flange 22 more and more firmly between the surfaces 12 and 17. The effect of such wedging will be to shift the flange 15 of the master plates toward the web 4 of the rail, thus tending to rotate the flange 16 thereof like a bell crank lever and cause it to press upwardly beneath the head 3. In other words, the downward movement of the flange 22 is converted into a sidewise movement of the flange 15, which is converted into an upward and inward movement of the web 14, which is converted into an upward and outward movement of the flange 16, which is prevented by the surface 6 of the head and the surface 19 of the flange 23, the net result being a wedging apart of the surfaces 6 and 19.

It will be seen that the bolts are not used for directly securing together the ends of the rails but merely to prevent the displacement of the securing parts and to produce a wedging action between certain of said securing parts so as to increase the firmness of their contact. Furthermore, the necessity for perforating the rail web has been avoided and the consequent weakening of the rail eliminated while the ends of adjacent rails are left comparatively free to move relatively under the influence of temperature changes. Furthermore, all the parts of my improved joint are such as can

readily be manufactured by simple processes of forging or rolling and are hence susceptible of cheap and rapid manufacture from tough and homogeneous metal. It is however, obvious that many changes in matters of detail might be made without departing from the scope of my invention, and I do not propose to be limited to such details excepting as the same may be positively included in the claims hereto annexed or may be rendered necessary by the prior state of the art.

Having thus described my invention, what I claim is:

- 15 1. A joint for T rails comprising, in combination, a bed plate having a longitudinal channel adapted to receive the ends of adjacent rails, plates adapted to overlap the sides of said rails and spaced from the sides of said channel, vertical wedge members adapted to be interposed between said side plates and the sides of said channel, the upper parts of said wedge members being braced against the lower sides of the head of the rail.
- 20 2. A joint for T rails comprising, in combination, a bed plate having a longitudinal channel on its upper face adapted to receive the abutting ends of adjacent rails, the sides of said channel flaring outwardly at a less angle to the vertical than the bottom of the rail head, plates adapted to overlap the ends of said rails at the side of the web and spaced from the sides of said channel, and wedge members interposed between said plates and the sides of said channel, the upper parts of said wedge members being braced against the lower side of the head of the rail.
- 25 3. A joint for T rails comprising, in combination, a bed plate having a longitudinal channel on its upper face adapted to receive the abutting ends of adjacent rails, the sides of said rails at the side of the web and spaced from the sides of said channel, the upper edges of said plates being in engagement with the bottom of the rail head and wedge members interposed between said plates and the sides of said channel, the upper part of said wedge members being in engagement with the sides of said plates.

4. A joint for T rails comprising, in combination, a bed plate having a longitudinal channel on its upper face adapted to receive the abutting ends of adjacent rails, plates adapted to overlap the ends of said rails at the side of the web and spaced from the sides of said channel, the upper edges of said plates being in engagement with the bottom of the rail head, and the outer faces of said plates having longitudinal recesses therein, and wedge members interposed between said plates and the sides of said channel, the upper parts of said wedge members being braced against the upper walls of said recesses.

5. A joint for T rails, comprising, in combination, a bed plate having a longitudinal channel on its upper face adapted to receive the abutting ends of the adjacent rails, the sides of said channel being outwardly flared, plates adapted to overlap the ends of said rails at the side of the web and spaced from the sides of said channel, the upper edges of said plates being in engagement with the bottom of the rail head, and the outer faces of said plates being formed with downwardly facing abutments which project outwardly at a greater angle from the vertical than the corresponding side of said channel, and wedge members interposed between said plates and the sides of said channel, the upper part of said wedge members being braced against said abutments.

6. A joint for T-rails comprising the combination, with the imperforate abutting ends of adjacent rails, of a pair of plates on each side thereof, and bridging the joint therebetween, one of said plates extending from the head to the base of the rail adjacent to the rail-web, and the other plate being interlocked with the upper part of said first plate and extending downwardly adjacent thereto, and a supporting or base member beneath the ends of said rails and having at each side an abutment between which and the adjacent first plate said second plate is interposed.

In testimony whereof, I hereunto affix my signature in the presence of two witnesses.

JOHN W. HAWKINS.
